UNITED STATES PATENT OFFICE.

LORENZO D. HOOPER, OF COFFEYVILLE, KANSAS.

CAR-COUPING.

SPECIFICATION forming part of Letters Patent No. 293,466, dated February 12, 1884.

Application filed September 6, 1883. (No model.)

To all whom it may concern:

Be it known that I, LORENZO D. HOOPER, a citizen of the United States of America, residing at Coffeyville, in the county of Montgomery and State of Kansas, have invented certain new and useful Improvements in Car-Couplers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to automatic car-couplers which are adapted to be operated for uncoupling without entering between cars—as, for instance, from the top of a car or from a position alongside the track.

20 The invention consists in certain novel constructions and combinations of devices, which will be fully understood from the following particular description, in connection with the accompanying drawings, in which—

25 Figure 1 is a perspective view of a car-coupler constructed according to my invention. Fig. 2 is a longitudinal central section of the same. Fig. 3 is a view of the tumbler and its pin detached from the draw-head.

30 The letter A indicates a draw-head, which is hollow, and approximately rectangular in cross-section, with a flaring mouth or open front end, the rear end being closed and attached to the draw-bar B, which may be secured to a car in any ordinary manner. The head A is preferably cast in one piece with the draw-bar. Transversely in the upper front portion of the draw-head is pivoted a tumbler-plate, C, which inclines rearwardly and downwardly from its pivot. From the center of the front surface of the tumbler-plate C projects an inclined frog or rib, D, having a heel, d, which projects below the edge of the tumbler-plate and normally rests upon the bottom of the draw-head. From the rear surface and near the lower edge of the tumbler-plate rises an arc-shaped hollow lug, E, which extends upward through a slot or opening in the top of the draw-head, and is provided with a rib, 35 e, on its rear surface. Longitudinally through the lug E is arranged a straight pin, F, pro-

vided with a head, f, having a rearwardly-open slot, and when this head rests upon the top of the lug E the tip or lower end of the pin projects through a hole in the bottom of the draw-head, just behind the heel d of the frog D. An arched bar, G, extends across the top of the draw-head, passing through the slit in the head f of pin F, and having its legs pivoted to the opposite sides of the draw-head by means of the projecting ends of the pivot-pin of the tumbler-plate. The legs of this arched bar are extended beyond their pivotal points, as shown at g, and bent so that they depend vertically in rear of the front end of the draw-head when the arched portion of the bar lies back, when the pin F is down. This pin has an elongated notch or slot in its back between two shoulders, s s', and transversely through this notch passes a pin, p, which is secured 65 through the lug E. The elongated notch allows the pin F a certain longitudinal play; but the lower shoulder, s, by striking the pin p, prevents the said pin F from slipping upward out of the lug E. The rib e of the lug E is 70 notched or slotted transversely at t, and upon the top of the draw-head is pivoted a latch, q, which may be engaged in the slit for holding upon the tumbler-plate and pin F, when it is desired to throw the coupler out of operation 75 for the usual purposes.

Suitable cords, k, as shown in dotted lines, may be attached to the extensions g of the legs of arched bar G, and extended to the top of the car, or through suitable guides to one or 80 both sides thereof, so that by drawing on said cord or cords the extensions g may be swung rearward and the arched bar G caused to rise and lift the pin F first, and then the tumbler-plate C and its frog, when the lower shoulder, 85 s, strikes pin p, so as to allow the coupling-link L to escape for uncoupling two cars.

It will be seen that the lower edge of the tumbler-plate C stands directly above the rear end of the link L, and thus holds the link in 90 a horizontal position, so that its outer end will enter another coupling. In entering a draw-head the end of a link will strike the inclined rib or frog D and raise it, the tumbler-plate, and pin F, so that the entering end of the link 95 will pass behind the heel d and strike the pin F, which will then be in an inclined position,

and also slip behind the pin, which, with the tumbler-plate, will then fall and engage the link.

It will be noticed that the pin F, when down, stands at right angles to the line of draft, and moves in a right line. When first lifted by the arched bar G, it moves independently of the tumbler-plate until it escapes from the link, and just as it escapes the shoulder s strikes the pin p and lifts the tumbler-plate, so that the heel d escapes from the link before the latter has time to be drawn forward against it. Thus I obviate the necessity for slackening or running back the link to permit the heel to escape, as would otherwise be the case, owing to the fact that said heel must move rearwardly in rising.

I preferably surround the lug E with a light spiral spring at v, one end of which bears against the tumbler-plate and the other against the top of the draw-head. This spring prevents the tumbler-plate from bounding upward, owing to the jarring of the cars while running. The rear wall of the draw-head holds the link forward, so that it will properly enter and operate the locking devices of another coupling.

It is a special advantage of my improved coupler that, if a car is thrown off the track and tilts or upsets, the consequent twisting or turning of the link causes it to raise the tumbler-plate and assume an edgewise oblique po-

sition, resulting in its disengagement from the pin and heel d, so that the derailed car will be automatically uncoupled.

Having now fully described my invention and explained the operation thereof, I claim—

1. The combination, with the hollow draw-head having openings in top and bottom plates, inclined pivoted tumbler-plate C, having frog D, with projecting heel d and hollow lug E, straight pin F, having a limited play in said lug and provided with the slotted head f, and the arched bar G, engaging said slotted head and having its legs pivoted to the opposite sides 45 of the draw-head, substantially as described.

2. The combination, with the draw-head, pivoted tumbler-plate having hollow lug E, and sliding pin F, having slotted head f, of the arched bar G, engaging said head and having 50 its legs pivoted to the opposite sides of the draw-head, and provided with the extensions g, substantially as and for the purpose set forth.

3. The combination, with the draw-head and inclined tumbler-plate having lug E, provided 55 with notched rib e, of the latch q, arranged to engage said rib, substantially as described, and for the purpose set forth.

In testimony whereof I affix my signature in presence of two witnesses.

LORENZO D. HOOPER.
